UNITED STATES PATENT OFFICE.

PHILIP BRECHER, OF LOUISVILLE, KENTUCKY.

HEATER.

SPECIFICATION forming part of Letters Patent No. 253,969, dated February 21, 1882.

Application filed September 17, 1881. (No model.)

To all whom it may concern:

Be it known that I, PHILIP BRECHER, of Louisville, in the county of Jefferson, and in the State of Kentucky, have invented certain new and useful Improvements in Heaters; and I do hereby declare that the following is a full, clear, and exact description of the invention, reference being had to the accompanying drawings, and to the letters of reference marked thereon, making a part of this specification.

My invention relates to the class of heaters or stoves which are applied to mantels or open-grate fires as now employed for heating rooms or apartments; and the object is to readily apply such heaters to mantels or open grates, as also to adjust them within the space now usually occupied by an ordinary grate-fire in a mantel to heat the apartment in which it is placed, and to heat upper or other apartments by the same heater, if desired, by making the proper connections, or to use and apply the same as a separate and distinct stove or heater in any position within the room to be heated, where it can be made to act as an open-grate fire, and making the proper connections with the hot-air flues, if also upper apartments are to be heated, and the ordinary flue or chimney.

The invention consists in the construction and arrangement of parts, as will be more fully described hereinafter, reference being had to the accompanying drawings, in which—

Figure 1 represents a perspective view of my improved heater applied to a mantel. Fig. 2 is a vertical cross-section of the same. Fig. 3 is a horizontal section on line *y y*. Fig. 4 is a horizontal section on line *x x*. Fig. 5 is a front view of the plate *A* or fire-back, showing the novel arrangement of the hollow pins projecting into the combustion-chamber.

In the drawings, *A* is the back of the fire-box or fuel-receptacle *A'*, which is provided with the ordinary grate. The back *A* is provided with two or more rows of hollow projections or pins, *a*, arranged in a staggering manner, as shown in Fig. 5, which project into the fire-box *A'* to furnish additional heating-surface to divide the products of combustion, gases, and smoke, in their upward passage to the flue *H'*, leading to the chimney, for the purpose of admitting air and flame to penetrate the dense smoke and gases, which are generated immediately above the fire contained in

the grate, (especially when fresh fuel is added,) thereby to more thoroughly consume the smoke and gases and generate more heat and save fuel. The object of placing these hollow pins or projections to extend into the fire-box or combustion-chamber *A'* above the grate in a staggering manner (see Fig. 5) is to divide and redivide the ascending products of combustion while passing to the flue *H'* and chimney, thereby more freely admitting the outward air and flame from the bottom of the grate to penetrate the dense gases and smoke, especially when fresh fuel is added, whereby the gases and smoke are more thoroughly consumed. By this arrangement of the parts the soot is in part prevented from lodging and forming on the surfaces of the combustion-chamber, and the draft is aided. The outward air will force itself into the spaces where the products of combustion are divided by the projections or pins, commingling with the gases and smoke, igniting the same more thoroughly than in the style of corrugated fire-backs heretofore employed, presenting more heating-surface, and giving off more heat to the front of the opening into the room when used as an open-grate fire in any position in the room to be heated, with doors *C C* drawn back or opened, generating more heat and saving fuel thereby. As the pins or projections become intensely heated, aiding in the combustion, as above stated, they also emit the heated air from the inside of the hollow pins into the air-space *B*, formed in the rear. Currents are also caused therein, whereby the air contained within it becomes more thoroughly heated than in the ordinary heaters. The air so emitted forces itself to the upper portions of the chamber *B*, where it will pass out through the hot-air passages or vents *H H* or the register *G*, as they may be adjusted, the cooler air remaining in the lower spaces, as is well understood, whereby the hottest air contained in the chamber only is utilized for the purposes intended.

The air-chamber *B* is divided into two compartments by a reticulated or numerously-perforated partition or diaphragm, *M*. As the heated air forces its way to the top of the chamber, passing out through the vents *H H* or register *G*, a vacuum is created, which will draw the cooler air from the lower chamber through the holes or perforations in the dia-

phragm in small jets or streams, whereby currents are generated, commingling with the hotter air, thus keeping up a continual circulation, and more thoroughly, evenly, and highly heating the air.

In the front part of the heater are the sliding doors C C, sliding in the grooves D D. The doors, when closed, act as a blower and damper, as in open-grate fires, or make the heater act 10 as a closed stove. When open all the benefits and comforts of an open-grate fire are obtained, as the heater in that position is an open-grate fire.

The lower fire-back, E, is provided with numerous perforations which communicate with a hot-air space, b, in the rear thereof, and suitable registers regulate the amount of air to be admitted to the air-spaces at the rear of the heater, as indicated by the arrows. The air-space b aids in the proper combustion of the fuel, and also prevents the fire back or lining from burning out or becoming destroyed by the direct action of the fire. The air is admitted to the space b by means of the register 25 N. The dampers in the vents H H, in combination with the register G, can be so adjusted that portions of the heated air contained in the chamber B will pass up through the vents H H to apartments above, and portions through 30 register G into the room where the heater is placed, as may be desired.

A deflector or hood, K, immediately above the register G, serves to diffuse the heated air back into the room in which the heater is 35 placed, and by deflecting and turning the heated air outward as it impinges against its outer surfaces, causing the same to diffuse itself more thoroughly in the lower portions of the apartment before rising directly upward, 40 according to the well-known laws of nature. It also prevents the ashes, dust, smoke, and cinders which may arise by the currents of hot air from the grate-fire when the doors are opened or drawn back from rising and lodging on the 45 mantel-piece or objects thereon.

The vents H H may be connected by an arch leading into the main hot-air flue directly in the center and above the smoke-flue H', whereby the heat emitted by the smoke-flue H', in 50 passing up the chimney, adds additional heat to the hot-air flue, utilizing the heat so emitted to heat the upper apartments, which would otherwise pass out of the chimney unused, less fuel being expended for the amount of heat so generated.

The register N regulates the amount of air required in the fire-box, and regulates the draft, &c.; and O is the cover of the ash-box; and any ornamental vase or pan, L', for containing water, &c., can be placed on the heater, if desired.

The register G in the front of the heater can, if desired, be adjusted to admit the air heated in the air-space B into the room, or when closed 65 it will prevent the escape of the heated air, excepting through the vents H H, which lead

to the upper rooms or apartments. The double damper I in the mouths of the flues H H, when closed, will compel the air to enter the space J in the upper part of the heater, to be 70 more thoroughly and highly heated therein, and from thence it passes out through the register G into the room or apartment.

Having thus described my invention, what I claim, and desire to secure by Letters Patent, 75 is—

1. A heater having a fire-back, A, with hollow air-circulating chambers projecting into the fire-chamber formed by the walls of the teats a, and communicating with a hot-air 80 chamber in rear of said plate A, substantially as described.

2. The combination, in a heater, of a fire-back, A, with hollow projections or teats a, arranged staggering, the two hot-air chambers 85 in rear of said plate, and a reticulated or air-jet diaphragm between said chambers, substantially as described.

3. A heater having a fire-back, A, provided with hollow projections or teats a, an air-space, B, divided by a numerously-perforated diaphragm, M, in combination with the lower 90 perforated fire-back, E, air-space b, passage N' leading into this space, and the registers F N, substantially as described. 95

4. The combination of a fire-box, A', an inclined back, A, provided with hollow projections a, arranged staggering, a divided air-space, B, a lower perforated fire-back, E, an air-space, b, passage, N', registers F G N, 100 heating-chamber J, damper I, flues H H', doors C, and a deflector or hood, K, all arranged substantially as described.

5. In a heater, the combustion-chamber, provided with an ordinary grate, having a 105 fire back or wall, A, with a series of hollow pins or conical teats, a, cast thereon, which project into said combustion-chamber or fire-box, in combination with the upwardly and backwardly directed flue L, substantially as 110 described, and for the purposes specified.

6. In a heater, the combustion-chamber A', having a fire back or wall, A, provided with hollow pins or conical teats a, cast thereon, which project into and nearly across the fire-box, arranged in two or more rows in a staggering manner, as shown and described, and for the purposes specified. 115

7. In a heater, a combustion-chamber having a fire back or wall, A, provided with hollow pins or conical teats a, arranged in two or more rows in a staggering manner, whose outer surfaces project into and nearly across the fire-box, and whose inner surfaces or hollows lead into and form part of the air-chambers B in rear of the same, substantially as 120 shown and described, and for the purposes specified. 125

8. In a heater, a combustion-chamber with a fire back or wall, A, provided with hollow pins or conical teats a, arranged in two or more rows staggering, in combination with a di- 130

vided air-space, B, in rear of said wall, the said air-space being divided by a reticulated or numerously-perforated diaphragm, M, into two compartments, substantially as described, 5 and for the purposes specified.

9. In a heater, a combustion-chamber having a fire back or wall, A, provided with hollow pins or conical teats *a*, arranged in two or more rows staggering, and an air-chamber, B, 10 divided into two compartments by the reticulated or numerously-perforated diaphragm M, in combination with the registers F N, substantially as described, and for the purposes specified.

15 10. In a heater consisting of a combustion-chamber having a fire back or wall provided with hollow pins or conical teats *a*, arranged in two or more rows in a staggering manner, whose outer surfaces project into and nearly 20 across the fire-box, and whose inner surfaces or hollows lead into and form part of the air-chamber B, which is divided by the perforated diaphragm M, the registers F N, in combination with the vents H H, dampers I I, hot-air 25 flue L, smoke-flue H', air-space J, register G,

and heat and dust deflector K, all arranged in the manner shown and described, and for the purposes specified.

11. In a heater, the combination of the combustion-chamber A', having a fire back or wall, 30 A, provided with hollow pins or conical teats *a*, cast thereon, arranged in two or more rows in a staggering manner, whose outer surfaces project into and nearly across the fire-box, and whose inner surfaces or hollows lead into and 35 form part of the divided air-chamber B, which is divided by a reticulated or numerously-perforated diaphragm, M, the registers F N, vents H, dampers I, arch and main hot-air flue L, smoke-flue H', air-space J, register G, hood or 40 deflector K, and doors C, all arranged substantially as described, and for the purposes specified.

In testimony whereof I affix my signature, in presence of two witnesses, this 13th day of 45 July, 1881.

PHILIP BRECHER.
